UNITED STATES PATENT OFFICE

136,548

DESIGN FOR AN UPPER BOWL FOR A COFFEE BREWER

Harvey Cory, Prescott, Ariz.

Application June 29, 1943, Serial No. 110,565

Term of patent 14 years

To all whom it may concern:

Be it known that I, Harvey Cory, a citizen of the United States, residing at Prescott, in the county of Yavapai and State of Arizona, have invented a new, original, and ornamental Design for an Upper Bowl for a Coffee Brewer, of which the following is a specification, reference being had to the accompanying drawing, forming a part thereof, wherein:

Fig. 2 is a side elevational view thereof, partly broken away in order to show a portion of the bowl wall in section, and the stem being shown broken away for convenience of illustration.

I claim:

The ornamental design for an upper bowl for a coffee brewer, as shown and described.

HARVEY CORY.
